UNITED STATES PATENT OFFICE.

WILLIAM F. A. BUEHNER, OF NEWARK, NEW JERSEY.

ADJUSTABLE POWER-RUDDER FOR SMALL BOATS.

1,330,842.

Specification of Letters Patent.

Patented Feb. 17, 1920.

Application filed August 11, 1917. Serial No. 185,690.

To all whom it may concern:

Be it known that I, WILLIAM F. A. BUEHNER, a subject of the Emperor of Germany, residing at Newark, in the county of Essex and State of New Jersey, have invented certain new and useful Improvements in Adjustable Power-Rudders for Small Boats, of which the following is a specification.

My invention relates to power-rudders for small boats.

One object of my invention is to provide a power-steering gear which can be quickly fastened and adjusted to any kind of stern of a boat.

Another object of my invention is to provide a lockable helm for the relief of the steering hand.

The drawings represent:

Figure 1, an elevation of a power rudder constructed according to my design.

Fig. 2, an elevation taken at right angles to the first,

Fig. 3, a plan view of a certain detail,

Fig. 4, a side view of the same,

Fig. 5, a section on the line 2—2 of Fig. 3,

Fig. 6, a plan view of another detail,

Fig. 7, a side view of the same, partly broken away.

The numerals indicate the following parts:

Numeral 1, a main frame to be rigidly attached to the stern of a boat by means of thumb screws 2. The usual motor frame consisting of a water-jacketed cylinder, a crank casing and a pipe like bearing for the driving shaft is pivoted to the main frame at 3 and has the extra support of two links 4 pivotally attached to the main frame and at 5 and slidably to the water-jacket of the cylinder and secured by thumb screws 6. A further support for the motor frame is given by a form 7 attached to the main frame at 8. A block 9 is slidably attached to one side of the fork and penetrates with a pin like projection 10 the other side 7' of the fork. Both sides can be swung upon the main frame and are held tight against block 9 by spring 11 held between the sides of the form upon projections 12 by pins 13 swinging away from block 9 of the fork side 7'.

and allows of moving of the motor frame relative to the main frame.

An auxiliary sleeve 14 over the pipe like bearing of the driving shaft passes through the perforated block 9 and is held from sinking by collar 15. The steering gear proper consists of sleeve 14, a hub 16 securely attached to it, a helm 17 attached to the hub 16 and a casing 18 containing the propeller shaft attached to sleeve 14 below the pipe like bearing of the driving shaft. Power is conveyed from driving shaft to propeller shaft through bevel gear 19 and the casing containing the propeller shaft and holding the propeller 20 can without hindrance be turned by the helm for steering purposes.

The construction of the lockable helm forms the second part of my invention as the adjustable motor frame without interference with engineering or steering forms the first part.

As to the second part which is particularly shown in Figs. 6 and 7, the helm 17 has an auxiliary lever 21 movably attached to it by pin 22 and within grip of the steering hand. The other end 23 of lever 21 is turned upward and rounded for the purpose of entering holes in a segment 24 which is securely attached to the water-jacket of the cylinder. When the lever 21 is in contact with the segment 24 and held thereby spring 25 between levers 17 and 21, the steering helm is locked in a certain position and the hand is relieved. When gripped by the hand the helm can be free for steering.

What I claim is:

1. The combination of an angular main frame adapted to be attached to a boat, an angular motor frame pivotally supported thereon and having its ends adjacent the ends of said angular main frame, means adjacent one end of said angular main frame exerting a constant pressure on the adjacent end of said angular motor frame to hold said motor frame adjusted relative to said main frame, and means adjacent the opposite end of said angular main frame engaging the adjacent end of said angular motor frame adapted to be fixed relative to said

angular motor frame to prevent displacement of the first mentioned means.

2. In an apparatus for power steering boats, a main frame, a motor frame pivotally supported thereon, links pivoted on the main frame, a sleeve on the motor frame, and yieldable means on the links for hold-

ing the links against the sleeve and thereby locking the motor frame in its desired adjusted position.

WILLIAM F. A. BUEHNER.
